UNITED STATES PATENT OFFICE

LEON BLOCH, OF CLEVELAND, OHIO, ASSIGNOR, BY MESNE ASSIGNMENTS, TO SPEAKMAN COMPANY, OF WILMINGTON, DELAWARE, A CORPORATION OF DELAWARE

SHOWER BATH HEAD

Application filed May 3, 1930. Serial No. 449,462.

This invention relates generally to a shower bath head and more particularly to an adjustable shower bath head by means of which the spray openings therein may be adjusted so as to vary the fineness of the spray.

The main object of the invention is to provide an adjustable shower bath head of the character described which comprises comparatively few parts which can be readily assembled or disassembled and which may be manufactured at comparatively low cost.

A further object of the invention is to provide an adjustable shower bath head in which the spray openings are disposed about the periphery thereof and which is provided with means for adjusting the sizes of these openings so as to vary the force and size of the spray.

A further object of the invention is to provide a shower bath head which consists essentially of inner and outer casings adjustably mounted with respect to each other, one of said casings having a plurality of spray openings disposed about the periphery thereof, together with simple and effective means for adjusting the relative position of said casings to vary the size of the spray openings.

Further and more limited objects of the invention will appear as the description proceeds and by reference to the accompanying drawings in which Fig. 1 is a vertical sectional view illustrating the preferred embodiment of my invention; Fig. 2 is a vertical sectional view on the line 2-2 of Fig. 1; Fig. 3 is a horizontal sectional view on the line 3-3 of Fig. 1; Fig. 4 is a fragmentary view in front elevation on a slightly exaggerated scale illustrating the shape of the openings provided about the periphery of the inner casing; Fig. 5 is a vertical sectional view disclosing a modified form of my invention; Fig. 6 is a fragmentary detail view in vertical section similar to Fig. 5 but showing the shower head adjusted to such a position as to permit maximum flow; Fig. 7 is a detail view partly in section and partly in elevation disclosing the adjusting member for adjusting the fineness of the spray; and Fig. 8 is a vertical sectional view on the line 8-8 of Fig. 5.

Referring now to the drawings, the refer-

ence character 1 designates a supply pipe having a threaded outer end over which is secured an outer casing 2 having a downwardly depending substantially circular portion 3 terminating in a flared substantially cup-shaped portion 4. Adjustably mounted within the outer casing 2 is an inner casing 5 having an annular portion 6 fitting within the substantially circular portion 3 of the outer casing, as shown most clearly in Fig. 1. The outer end of the inner casing is provided with a radially extending portion 7 terminating in an inwardly projecting peripheral flange portion, the inner end of which is exteriorly beveled so that the outer surface of said flange comprises an outer substantially straight face or cylindrical portion 8 and an inner angular face or conical portion 9. The inner casing 5 is open at its inner end and disposed in open communication with the supply pipe 1. The inner casing is also provided with a pair of oppositely disposed ports 10 and 11 which provide communication between the inner casing and the space between the inner casing and the outer casing.

Journalized in the outer casing 2 is a shaft 12 which is held in place by a packing 13 and a packing gland 14. The inner end of the shaft is provided with an eccentrically disposed portion or projection 15 which engages in a rectangular slot 16 provided in the inner casing 5. Secured to the outer end of the shaft 12 is an operating handle 17, by means of which the position of the inner casing with respect to the outer casing may be adjusted. Disposed about the periphery of the outer end portion of the inner casing are a plurality of substantially V-shaped notches 18 which cooperate with the adjacent inner peripheral of cylindrical wall of the outer casing to define a plurality of spray openings. As is clearly shown in the drawings, and particularly in Fig. 4, the notches or grooves 18 extend in the general direction of the axis of the cylindrical surface 8, but are inclined to said axis so that each groove terminates at its outer end in the cylindrical surface 8 and terminates at its other end in the conical surface 9. Each groove 18 is thus tapered, increasing in cross section from each end to

the junction of the surfaces 8 and 9. It will be seen, therefore, that by adjusting the position of the inner casing with respect to the outer casing, the size of the spray openings 5 may be varied so as to obtain a very fine needle spray or a soft coarse spray. The shape of the notches in the periphery of the inner casing enables these spray openings to be finely adjusted or completely closed as desired. 10 Due to the shape of the notches 18 and also due to the fact that the notches are provided in the angular face 9 a very fine adjustment may be obtained. Due to the particular arrangement of parts and the shape of the notches 18, it will be seen that the effective size 15 of the spray openings is a straight line function of the relative position of the inner and outer casings.

In Figs. 5 to 8 inclusive there is disclosed 20 a slightly modified form of my invention. In this form of the invention the outer casing 19 is of slightly different shape and is threadedly secured to a supply pipe 20. The outer casing 19 is provided with an interiorly 25 threaded portion into which is secured a disk-like member 21 having openings 22, 23, 24 and 25 therein disposed as shown most clearly in Fig. 8. The member 21 is provided with a downwardly extending stem or guide portion 26 the purpose of which will hereinafter appear. Secured to the member 21 is a disk-like valve member 27 having a threaded stem portion 28 which engages in a threaded socket in the stem portion 26. The valve member 27 30 is provided with openings 29, adapted to be moved more or less into alignment with the openings 22, 23, 24 and 25, respectively. This valve member serves to adjust the rate 35 of flow of the liquid to the shower head.

40 Slidably and adjustably mounted on the stem or guide member 26 is a member 30 having a hollow stem portion 31 which fits over the stem 26. The lower end of the member 30 is substantially circular in shape and fits 45 within an annular recess provided in the lower end of the outer casing. The member 30 is shown in detail in Fig. 7 and is provided about its periphery with a plurality of angular notches or recesses 18^a of substantially 50 the same shape as the notches 18 described in connection with the embodiment of the invention shown in Figs. 1 to 4 inclusive. Journaled in the outer casing 19 is a shaft 32 which is held in place by washer 33, packing 34 and 55 packing gland 35. The inner end of the shaft 32 is provided with an eccentrically disposed crank or projection 36 which is adapted to engage in a recess or notch provided in the upper end of the stem 31 as shown most clearly in Fig. 5. Secured to the other end of the shaft 32 is an operating lever or handle 37 by means of which the position of the inner member 30 may be adjusted with respect to 60 the outer casing 19. It will, therefore, be seen that by adjusting the position of the

member 30 with respect to the outer casing the effective size of the spray openings may be varied so as to obtain a very fine needle spray or a soft coarse spray. The shape of the notches about the periphery of the member 30 enables these spray openings to be very finely adjusted. Disposed between the valve member 27 and the stem 26 is a coil spring which surrounds the stem 28 and which serves to place a slight tension on the valve member 70 to maintain it in the adjusted position. By adjusting the position of the valve member 27 the effective size of the openings 22, 23, 24 and 25 may be adjusted so as to vary the rate of flow therethrough. The parts are so designed that the member 30 may be moved to the position shown in Fig. 6 whereupon the water will be delivered from the shower head in an annular sheet rather than as a spray. In other respects this form of the invention 80 is substantially the same as the form of the invention disclosed in Figs. 1 to 4 inclusive.

It will now be clear that I have provided an adjustable shower bath head which will accomplish the objects of the invention as 85 hereinbefore stated. Various changes may be made in the shape, size and arrangement of the various parts without departing from the spirit of my invention. The particular manner of adjusting the relative position of 90 the inner and outer casings may also be modified without departing from the spirit of my invention. It is therefore to be understood that the embodiments of the invention herein disclosed are merely illustrative and are not 95 to be considered in a limiting sense and that the invention is limited only in accordance with the scope of the appended claims.

Having thus described my invention, what I claim is:

1. A shower bath head comprising a supply pipe, an outer casing secured thereto, an inner casing adjustably mounted within said outer casing and disposed in open communication with said supply pipe and with said outer casing, said inner casing having a substantially annular end portion having a plurality of peripheral notches therein extending in the general direction of the axis of said annular portion and each tapered in the direction of its length cooperating with the wall of said outer casing to define a spray opening through which water supplied to said casings by said supply pipe is discharged, and means for adjusting the position of said inner casing to vary the size of said spray opening.

2. A shower bath head comprising an outer casing having one end threadedly secured to a supply pipe, and its opposite end flared outwardly to provide a substantially cup-shaped portion, an inner casing adjustably mounted in said outer casing and having a peripheral surface fitting within the cup-shaped portion of said outer casing, and hav-

- ing tapered angular notches disposed about the periphery cooperating with the wall of said outer casing to define spray openings through which water supplied to said casing 5 is discharged, and means for adjusting the relative position of said casings to vary the size of said openings.
3. A shower bath head comprising an outer casing having one end threadedly secured to a supply pipe and its opposite end flared outwardly to provide a substantially cup-shaped portion, an inner casing adjustably mounted in said outer casing and having a peripheral surface fitting within the cup-shaped portion 10 of said outer casing, said surface comprising a cylindrical outer portion and a conical inner portion and having peripherally disposed substantially V-shaped notches each formed partly in said conical surface portion and 15 having its outer end in said cylindrical surface portion, and means for adjusting the relative position of said casings in the direction of the axis of said cylindrical surface portion.
- 20 4. A shower bath spray head, embodying a hollow casing; a closure disk for the open end of the casing, the circumference of the disk slidably fitting the annular surrounding inner surface of the casing to permit relative longitudinal adjustment between the casing and disk, one of said annular surfaces formed with an annular series of spaced vertical 25 downwardly shallowing water jet forming grooves covered by the other annular surface, the shallow lower ends of which constitute the jet discharge orifices, the capacities of 30 which are varied by vertical adjustment of said disk, and supporting means for the disk and whereby the same is rendered vertically 35 adjustable.
5. A spray head embodying a housing having a pressure water inlet, the lower portion of the housing having a cylindrical vertical inner surface terminating in a downwardly 40 enlarged skirt; a vertically adjustable closure disk for and in the bottom of said casing, the circumference of said disk having an annular series of grooves extending throughout the vertical length thereof and decreasing in 45 depth downwardly, the circumference of the disk engaging said cylindrical inner surface of the casing with a running fit, and supporting and adjusting means for said disk, whereby the disk can be lowered within said cylindrical portion to increase the capacity of the 50 outlet ends of said grooves, and whereby the disk can be dropped below said cylindrical portion for flushing and cleansing the 55 grooves.
- 60 6. A spray head embodying a housing having a pressure water inlet, the lower portion of the housing having a cylindrical vertical inner surface; a vertically adjustable closure disk for and in the bottom of said casing, the circumference of said disk having an annular 65
- series of grooves extending throughout the vertical length thereof and decreasing in depth downwardly, the circumference of the disk engaging said cylindrical inner surface of the casing with a running fit, and supporting and adjusting means for said disk, whereby the disk can be lowered within said cylindrical portion to increase the capacity of the outlet ends of said grooves, and whereby the disk can be dropped below said cylindrical portion for flushing and cleansing the 70 grooves.
7. A shower bath spray head comprising in combination a shell formed with a single water outlet opening, the cross sectional area of which is approximately equal to the maximum internal cross sectional area of said shell, a flow obstructing device extending into and adjustable longitudinally of said opening and formed with a multiplicity of narrow grooves extending longitudinally of said opening and varying in cross section in the direction of their lengths and uniting with the wall of said outlet opening to form flow channels the aggregate cross sectional area of 75 which is varied by the longitudinal adjustment of said device in said outlet opening, and means for adjusting said device longitudinally of said opening.
8. A shower bath spray head comprising in combination a shell formed with a water inlet and with a single circular water outlet opening, the cross sectional area of which is approximately equal to the maximum internal cross sectional area of said shell, a flow obstructing device of generally circular outline extending into and adjustable longitudinally of said outlet opening and formed with a multiplicity of narrow peripheral 80 grooves extending longitudinally of said opening and varying in cross-section in the direction of their lengths and uniting with the wall of said outlet opening to form flow channels the aggregate cross sectional area of 85 which may be varied by longitudinal adjustment of said device in said outlet opening, the aggregate width of said grooves in their outer end portions being equal to a small fraction only of the circumference of said device, and means for adjusting said device longitudinally of said outlet opening.
9. A shower bath head comprising a casing member formed with an outlet opening the inner wall of which is cylindrical, a member having a peripheral surface comprising a cylindrical outer end portion extending into and fitting in said opening and a conical portion at the inner side of said cylindrical portion, and having peripherally disposed grooves which extend in the general 90 direction of the axis of said opening but are inclined thereto and which cooperate with said inner wall to define spray openings and each of which comprises an inner portion formed in said conical surface portion and an 95

outer portion ending in said cylindrical surface portion, and means for adjusting said member axially of said outlet opening to thereby vary the size of said spray openings.

- 5 10. A shower bath head comprising a supply pipe, an outer casing secured thereto, an inner casing adjustably mounted within said outer casing and comprising a disc portion extending across the space within the outer casing with a flange at its periphery and having a plurality of notches in its peripheral surface extending in the general direction of the axis of said disc and flange and each tapered in the direction of its length and cooperating 15 with the wall of said outer casing to define a spray opening through which water supplied to said casings by said supply pipe is discharged, and means for adjusting the position of said inner casing to vary the size of 20 said spray opening.

In testimony whereof, I hereunto affix my signature.

LEON BLOCH.
